UNITED STATES PATENT OFFICE.

WALTER G. CLARK, OF NEW YORK, N. Y.

EXCAVATING-MACHINE.

1,082,501.

Specification of Letters Patent. Patented Dec. 30, 1913.

Application filed November 21, 1911. Serial No. 661,477. Renewed May 15, 1913. Serial No. 767,902.

To all whom it may concern:

Be it known that I, WALTER G. CLARK, a citizen of the United States, and a resident of the borough of Manhattan, city, county, and State of New York, have invented certain new and useful Improvements in Excavating-Machines, of which the following is a specification, accompanied by drawings.

This invention relates to excavating machines having a power actuated excavating device, as a shovel or scoop, and the objects of the invention are to improve upon the means for actuating and controlling the excavating device, so that the power may be directly applied to the excavating device and efficiently and readily controlled within the desired limits to produce the required movements.

Another object of the invention is to enable the movements of the excavating device to be speedily controlled by direct acting means, so that the adjustments in different positions may be effected efficiently without loss of time and power.

Further objects of the invention will hereinafter appear and the invention consists of the apparatus substantially as hereinafter fully described and claimed in this specification and shown in the accompanying drawings, in which—

Figure 1 is a broken side elevation, partly in diagrammatic form, of an excavating machine embodying the invention; Fig. 2 is a diagrammatic broken plan view of the machine, with parts removed; Fig. 3 is a diagrammatic plan view of the actuating devices and connections.

Referring to the drawings, A represents the base or frame of the machine, provided with the wheels B adapted to travel on the tracks C. The working member or excavating means, may be of any suitable type, but I prefer a boom D pivoted for vertical movement at E upon a turn-table F mounted upon the forward end of the frame A, said boom being provided with a shovel arm G carrying a scoop or shovel H. The shovel arm G is capable of both longitudinal and swinging movement in the usual manner, and operatively connected power actuated means are provided for hoisting and lowering the shovel arm and shovel, for rotating the turn-table, to turn the boom, and for forcing or crowding the scoop or shovel, by

imparting the proper movement to the shovel arm. The boom D is suitably supported from its outer end, as by means of the guy wire I loosely connected to the upper end of the strut or stay J, which is in turn supported from the frame by the guy wire K.

I prefer to use hydraulic or pneumatic pressure, or a combination of the two, for actuating and controlling the excavating means, and in accordance with this invention the actuating means are direct acting, thereby avoiding the use of intermediate or auxiliary operative parts, and increasing the efficiency and rapidity of operation.

An important feature of the invention consists in the arrangement and operative connections of the forcing or crowding cylinders L, which I prefer to mount in any suitable manner directly upon the boom D, as by means of the supports M. The piston rods N of cylinders L are connected to actuate the shovel arm G directly, so that the direct thrust of the pistons is imparted to the shovel arm for forcing or crowding the shovel. A suitable form of construction is that shown in the drawings, in which the piston rods N are provided with racks O slideable on guide rollers P and meshing with pinions Q on the outer ends of the shaft R mounted transversely on the boom D. Between the sides of the boom and upon shaft R is conveniently fixed a pinion S meshing with a rack T provided on the under side of the shovel arm G; so that as the pistons and piston rods of cylinders L are forced outwardly, the pinions Q and S are rotated in a direction to draw the shovel arm G transversely and upwardly across the boom. On the return stroke, the shovel arm is moved in the opposite direction across the boom.

The scoop or shovel H may be of any suitable or usual type which will not be described in detail, as it forms no specific part of the invention. A hoisting cylinder U is mounted in the frame A in a convenient location, preferably substantially midway between the sides, and operatively connected to hoist and lower the shovel H. As shown, the piston rod V is provided with a pulley W, and a rope or chain X is suitably fixed at one end at a to a stationary part of the apparatus, and thence passed over the pulley W, then over the guide pulleys Y and Z,

thence over the guide pulley *b* at the outer end of the boom, and connected at *c* to the shovel *H*. The hoisting cylinder is thus directly connected for hoisting the shovel. As 5 the piston and piston rod of hoisting cylinder *U* move outwardly, the rope *X* is drawn backwardly, and the shovel is hoisted.

Turning cylinders *d* and *e* are suitably mounted on the frame *A*, preferably above 10 the hoisting cylinder, and directly connected to actuate the turn-table *F*. The piston rods *f* of the turning cylinders are provided with pulleys *g*, and a rope or chain *h*, is suitably fixed at one end at *j* to a stationary 15 part of the apparatus, thence passed over one pulley *g*, thence over guide pulley *k* and around the grooved edge *m* of the turn-table *F*, thence over a corresponding guide pulley *k* at the other side of the machine, 20 and over the pulley *g* on the other piston rod *f* and fixed to the machine. The turn-table receives the direct pull of either turning cylinder, and will be turned in one direction or the other according to the turning 25 cylinder to which pressure is supplied.

In accordance with this invention, the outward strokes of the hoisting cylinder *U*, and the forcing or crowding cylinders *L* are preferably operated by hydraulic pressure, from a hydraulic pressure system supplied by a suitable pump *n*, which may be a 30 rotary pump, mounted on the frame and driven by any suitable means as an electric motor *o* connected thereto. The water is preferably pumped into air and water receiver tanks *q* and *r* and stored under air pressure furnished by a suitable compressor *s* preferably of the plunger type driven by a suitable electric motor *t*. The compressor 35 *s* is preferably connected to an air reservoir *u* which is connected to the receiver tanks *q* and *r*, so that pneumatic pressure is superimposed upon the hydraulic system. The return strokes of the hoisting and forcing 40 or crowding cylinders are preferably controlled by pneumatic pressure, and as the turning cylinders oppose each other, these cylinders are conveniently constructed to be single acting, and operated from the hydraulic pressure system, suitable controlling 45 valves being provided for both the hydraulic and pneumatic systems, which valves may be independently actuated, or any desired set of valves may be connected together by suitable means, for automatically actuating 50 several valves at the same time.

The pipe connections for the apparatus will be best understood by reference to the diagrammatic representation of the cylinders and piping shown in Fig. 4, in which as far as possible, corresponding parts have 55 been designated by reference characters similar to the remaining figures.

The water discharge 2 of the pump *n* is

connected by discharge pipe 3 with the 65 junction 4, and from thence a pipe 5 supplies the receiver *r*, preferably at the bottom. A connecting pipe 6 leads from the elbow 7 beneath tank *r* to the bottom of receiver tank *q*, and from the elbow 8 beneath 70 said tank, a return pipe 9 leads back to the intake 10 of the pump. A valve and valve casing 11 is interposed in the return pipe 9 intermediate the tank *q* and the pump, by means of which the circulation of the water 75 may be shut off, after sufficient water has been stored in the receivers *q* and *r* under the desired air pressure. The valve stem 12 for the valve in casing 11 may be manipulated to open and close this valve as the 80 necessities of the system require. In Fig. 1 the valve in casing 11 is assumed to be closed and circulation cut off.

The hoisting cylinder *U* is connected with the hydraulic pressure system as follows: The pipe 13 leads from the junction 4 to the pipe 14 which in turn leads to the forward end of the hoisting cylinder *U*. A valve casing 15 is interposed in the pipe 13 between the junction 4 and the pipe 14 and 85 provided with a suitable valve having the valve stem 16. This is the supply valve for the hoisting cylinder and is shown closed in Fig. 1. From the junction of the pipes 13 and 14 a return pipe 17 leads to the intake 90 10 of the pump and a valve casing 18 is interposed in said return pipe, provided with a cut off valve having the valve stem 19. This valve is shown open in Fig. 1. The pipe 14 is both the supply and return for 100 the water to and from the hoisting cylinder *U* and with the valves in the valve casings 15 and 18 in the position shown, the piston of the hoisting cylinder *U* has made its return stroke and the water has been returned 105 to the pump *n*. The pneumatic connections for furnishing pneumatic pressure for returning the piston of the hoisting cylinder will hereinafter be described.

The hydraulic connections for the turning cylinders *d* and *e* are as follows: A supply pipe 20 leads from the junction 4 to a valve casing or junction box 21 and from thence branch pipes 22 and 23 lead to the turning cylinders *d* and *e* respectively. A 110 suitable two-way valve (not shown) is provided in the valve casing 21 by means of which one turning cylinder may be supplied with hydraulic pressure for the working stroke, while the other turning cylinder is 115 being exhausted. Water from the turning cylinders is returned through pipe 24 connecting the valve casing 21 with the intake 10 of the pump.

The hydraulic connections for the crowding cylinders *L* are as follows: A pipe 25 connects the supply pipe 20 at the top of the valve casing 21 with a valve casing 26

and a pipe 27 connects casing 26 with the elbow 28 provided with the T-connection 29 in the form of a swivel to which the branch pipes 30 are connected leading to the inner ends of the crowding cylinders L. Since the elbow 28 to which the swivel 29 is connected is stationary and the branch pipes 30 move up and down and turn with the crowding cylinders L, provision, such as described, is necessary to provide for relative movement at the junction between the stationary and movable water connections. Water is supplied to and returned from the crowding cylinders L through the pipes 27 and 30 and a suitable valve (not shown) is provided in the valve casing 26 controlling the supply pipe 25 and the return pipe 31 connecting the casing 26 with the return pipe 24 for the turning cylinders, so that water is supplied to or returned from the crowding cylinders by manipulating the valve in casing 26. The pneumatic connections for operating the crowding stroke of the crowding cylinders will hereinafter be described.

Compressed air is supplied from the air storage tank u through pipe 32 preferably to the top of the receiver tank r and connecting pipe 33 leads from the elbow 34 to the top of receiver tank q, thus furnishing pneumatic pressure to said tanks above the water contained in them. Pneumatic pressure is supplied to the hoisting cylinder U in front of the piston for the return stroke 35 through the pipe 35 connecting with pipe 33. A return pipe 36 connects pipe 35 with the air return pipe 37 leading back to the compressor s. A suitable controlling valve 38 is provided at the junction of the pipes 35 and 36 and a suitable relief or safety valve 39 is provided in the return pipe 37. Valve 38 may be manipulated to supply pneumatic pressure for the return stroke of the piston in the hoisting cylinder U and for exhausting the air from said cylinder during the working stroke for which hydraulic power is supplied.

An air supply pipe 40 connects supply pipe 33 with a valve casing 41 from which a pipe 42 leads to a casing 43 to which is connected a swivel 44. Branch pipes 45 connect said swivel with the outer ends of the crowding cylinders L. The return pipe 37 connects the valve casing 41 with the compressor s. A suitable valve (not shown) in the casing 41 controls the supply and return of pneumatic pressure for the crowding cylinders L. The swivel connection 44 is required at the casing 43 in order to enable the pipes 45 to move up and down and to turn relatively to the stationary pipe connection at this point.

The operation of the apparatus is briefly as follows: With the parts in the positions

indicated in Fig. 1, the circulation of water 65 through the receiver tanks q and r has been cut off by the closure of the valve in the casing 11, controlling the return pipe 9 leading back to the intake 10 of the pump n, and sufficient water has been stored in the tanks q and r under the desired pressure for operating purposes. The supply valve in the casing 15 for the hoisting cylinder U controlling the supply of hydro-pneumatic pressure to said cylinder is closed in Fig. 1, 75 and the piston of cylinder U is in retracted position, ready for the application of hydro-pneumatic pressure behind the said piston to force it outwardly for hoisting. The pistons of the turning cylinders d and e are in 80 retracted position in Fig. 1 and the two-way valve in the casing 21 is in such position that hydro-pneumatic pressure is cut off from the turning cylinders. The pistons of the crowding cylinders as shown in Fig. 1 85 are at some intermediate point in their travel, and the valves in the casings 26 and 41 are closed. In order to adjust the angle of the boom about a vertical axis, the two-way valve in casing 21 is manipulated to 90 admit hydro-pneumatic pressure through pipe 20 to one turning cylinder d or e while exhausting pressure from the other cylinder back to the pump through the pipe 24. In order to raise the shovel arm G, the valve 95 in the casing 15 is opened to admit hydro-pneumatic pressure behind the piston of the hoisting cylinder U, and the air valve 38 is manipulated to connect the space in front of the piston with the air return pipe 37. 100 To lower the shovel arm G, the air valve 38 is turned to admit air to the cylinder U, the supply valve in casing 15 is closed, and the exhaust valve in casing 18 is opened, to permit the water to return from behind 105 the piston in cylinder U to the pump. In order to crowd the shovel, the valve in casing 41 is moved to connect the outer ends of the crowding cylinders L with the air supply pipe 40, and the valve in casing 26 110 is moved to permit the return of water from the crowding cylinders through pipes 31 and 24 to the pump. The crowding is thus obtained with pneumatic pressure. The shovel arm G is retracted by opening the 115 valve in casing 41 to the air return pipe 37, and moving the valve in casing 26 to admit hydro-pneumatic pressure to the crowding cylinders.

Having described the construction, operation, and operative connections, both mechanical, hydraulic and pneumatic, for the various component parts of the apparatus, the controlling valves may be manipulated as desired for turning the boom into the desired position, for hoisting or lowering the shovel and for forcing or crowding the shovel, and obviously several operations, as

hoisting and forcing or crowding, may be carried out at the same time, as desired. The direct connection of the forcing or crowding cylinders *L* with the excavating device enables quick starts and stops to be effected and affords provision for exerting the maximum effort in forcing or crowding, while at the same time hoisting, thus producing the maximum efficiency under practical conditions. The machine is strong and durable and being of such simple construction with few parts to get out of order, heavy work may be carried on and the machine subjected to hard usage without stoppage for repairs.

One of the primary features of the invention consists in the flexibility of control of the working parts obtained by the combination of a hydraulic pressure system for actuating the excavating means with a pneumatic system superimposed upon the said hydraulic system. By this means the hydraulic system is always ready for immediate use and responds instantly when applied to the actuating devices. Another feature which adds to the flexibility of control, consists in the provision for returning the piston of the hoisting cylinder by pneumatic pressure, which is instantly available, so that the speed at which the machine may be operated is increased. The valve in the casing may, if desired, be left open during all the operations, and this is preferable, because the return to the tank *q* is then open directly through pipe *g* and the working pistons of the apparatus may be subjected either to the combined kinetic and static pressure, or to the static pressure alone. The compressor *s* and air reservoir *w* compensate for any loss of pressure in the receiver tanks at all times.

I claim and desire to obtain by Letters Patent the following:

1. In an excavating machine, the combination with an excavating device, of a main pump, a receiver tank, a closed circulating pipe system including said main pump and receiver tank, means for controlling the flow of fluid through said closed circulating system to the pump, a source of air pressure, air connections from said source to the receiver tank, a working cylinder, branch connections from said circulating pipe system to one end of the said working cylinder and means for controlling said branch connections, and return connections for the fluid from the working cylinder to the pump, and means for controlling said return connections, whereby the piston of the working cylinder may be subjected to the combined static pressure of the receiver tank and to the energy due to the motion of the circulating fluid, or subjected to the static pressure alone.

2. In an excavating machine, the combination with an excavating device, of a main pump, a receiver tank, a closed circulating pipe system including said main pump and receiver tank, means for controlling the flow of fluid through said closed circulating system to the pump, a source of air pressure, air connections from said source to the receiver tank, a working cylinder, branch connections from said circulating pipe system to one end of the said working cylinder and means for controlling said branch connections, and return connections for the fluid from the working cylinder to the pump, means for controlling said return connections, whereby the piston of the working cylinder may be subjected to the combined static pressure of the receiver tank and to the energy due to the motion of the circulating fluid, or subjected to the static pressure alone, air connections to the opposite end of the working cylinder from that to which the branch from the circulating pipe system is connected, and means for controlling said air connections.

3. In an excavating machine, the combination with an excavating device, of a main pump, a receiver tank, a closed circulating pipe system including said main pump and receiver tank, means for controlling the flow of fluid through said system to the pump, a source of air pressure, air connections from said source to the receiver tank, a hoisting cylinder and a crowding cylinder, branch connections from said circulating pipe system to the hoisting end of the hoisting cylinder and to the returning end of the crowding cylinder, means for controlling said branch connections, and return connections for the fluid from the hoisting and crowding cylinders to the pump, whereby the pistons of the hoisting and crowding cylinders may be subjected to the combined static pressure of the receiver tank and to the energy due to motion of the circulating fluid, or subjected to the static pressure alone.

4. In an excavating machine, the combination with an excavating device, of a main pump, a receiver tank, a closed circulating pipe system including said main pump and receiver tank, means for controlling the flow of fluid through said system to the pump, a source of air pressure, air connections from said source to the receiver tank, a hoisting cylinder and a crowding cylinder, branch connections from said circulating pipe system to the hoisting end of the hoisting cylinder and to the returning end of the crowding cylinder, means for controlling said branch connections, return connections for the fluid from the hoisting and crowding cylinders to the pump, whereby the pistons of the hoisting and crowding cylinders may be subjected to the combined

static pressure of the receiver tank and to the energy due to the motion of the circulating fluid, or subjected to the static pressure alone, air connections to the lower-
5 ing end of the hoisting cylinder and to the crowding end of the crowding cylinder, and means for controlling said air connections.

In testimony whereof I have signed this specification in the presence of two subscribing witnesses.

WALTER G. CLARK.
